UNITED STATES PATENT OFFICE.

THOMAS W. HAMILTON, OF BERLIN, WISCONSIN.

LEGGING.

No. 872,727.

Specification of Letters Patent. Patented Dec. 3, 1907.

Application filed January 12, 1907. Serial No. 351,663.

To all whom it may concern:

Be it known that I, THOMAS W. HAMILTON, citizen of the United States, residing at Berlin, in the county of Green Lake and State of Wisconsin, have invented certain new and useful Improvements in Leggings; and I hereby declare the following to be a full, clear, and exact description of the invention, such as will enable others skilled in the art to which it appertains to make and use the same.

My invention relates to an improved legging, the object being to provide a heavy legging which can be easily and readily secured in position, which will lie snugly in place, without projecting fasteners, and which will effectually exclude the snow; and consists in the features of construction and combinations of parts hereinafter fully described and claimed.

In the accompanying drawings, illustrating my invention—Figure 1—is a side elevation, in perspective, of a legging made in accordance with my invention as it would appear from the right side when placed upon the right leg. Fig. 2—is a view similar to Fig. 1, except that two of the corners of the flaps or parts of the legging are turned back, for purpose of illustration.

The utility of leggings of this character is to protect the leg from abrasion and to exclude the snow. There are two styles of leggings in common use—one called the front lace and one, the side fastened, both of which are inefficient for the purpose intended.

The side fastened legging has buckles or other fastening devices on the sides which damage and wear out the linings of the long fur coats, worn by many who use leggings. The front lace legging commonly used has two or more flaps overlapping on the instep, and are therefore very bunglesome at this point, and it is difficult or impossible to fit an overshoe over them.

The specific object of my invention is to produce a legging which will accomplish all that is desired of such an article and at the same time overcome the objections common to leggings in use at the present time.

Referring now to said drawings, it will be seen that my invention relates particularly to what is known as the "front lace" style of legging, which is made to fit around the leg and fasten together down the front, one of the meeting edges being provided with hooks

and the other with eyelets, through which a lace may be threaded, which is adapted to be looped over the hooks on the opposite edge to draw the edges together. While I have illustrated this method of fastening, it should be understood that the particular form of fastening device is not a feature of my invention and that any other style may be used.

My legging is formed of two main parts or flaps A and B which are joined together down the back of the leg at C. The said flap A extends forward around the inside of and over the front of the leg and to about the middle of the outer side of the leg, and is provided at its lower end in front with the extension D formed to fit snugly over the instep, the lower end of said flap A reaching down well over the foot. Said portion of flap B extends forward around the outer side of the leg and ends adjacent the front of same, it is shorter in height than said flap A and extends from the top of same to about the ankle and is adapted to lie outside of the free end of said flap A. A third or supplemental flap E is joined to said flap A at its rear end and extends forward around the outer side of the leg beneath the lower end of said flap B and is adapted to lap beneath the rear edge of the free end F of said flap A, its lower edge being on a line with the lower end of said flap A and it extending upward a short distance above the ankle.

The lower end of the legging is adapted to be held snugly in place by means of the adjustable coacting fastening devices G and H which are such as are in common use and need no detailed description, said devices being adapted to draw the free ends of said flaps A and E together. It will be seen that the position of said fastening device G is such, in relation to the lower end of said flap B, that when the latter is in place said fastening device is covered, thus effectually preventing anything from catching on same. Said flap A is provided, adjacent the front of the leg, with a vertical line of hooks I and the free end of said flap B is provided with a line of eyelets through which a lace K is adapted to be threaded and by means of which said legging can be secured snugly in place around the leg in a well known manner.

A strap L is provided on the lower end of the legging to assist in holding the legging in place, in a well known manner.

It will be noted that in the construction of

my legging there is practically only one layer of the material over the instep thus making a smooth close fitting legging at this point.

My legging is readily mounted, the overlapping edges are held snugly in place and there are no exposed fastening devices to cause annoyance.

I claim as my invention.

1. A legging comprising a body portion 10 cut away at one of its lower corners, the side edges of said body-portion overlapping, lacing means disposed adjacent said overlapping edges, a flap secured to said body portion and projecting under said cut away portion, and fastening means disposed on said flap and said body portion.

2. A legging comprising a body portion 20 cut away at one of its lower corners, the side edges of said body-portion overlapping, lacing means disposed adjacent said overlapping edges, a flap secured to said body portion and projecting under said cut away portion, and fastening means disposed on said flap and said body portion, said fastening 25 means being covered by that portion of said body portion above said cut away portion.

3. A legging comprising a body portion 30 of flexible material having overlapping side edges, one end thereof extending from substantially the middle of the calf around the inner side and over the front of the leg, and the other end extending in the opposite direction to a point adjacent the front of the leg, said first named end overlapping the inner 35 side of the foot and the instep, and said other end being cut away at its lower end, a flap secured to said body portion by a line of stitching coincident substantially with the line of juncture of said ends and underlying 40 said cut-away portion and said first named end of said body portion at its free end, and

coacting fastening means disposed in operative relation to all of said ends.

4. In a legging, a body portion comprising two main flaps of unequal length secured together at one edge, the free edge of the shorter flap overlapping the free edge of the longer flap, fastening means disposed adjacent said overlapping edges, a supplemental flap secured to said body portion, and extending below the lower end of said shorter main flap, and fastening means carried by said supplemental flap and the longer of said main flaps.

5. In a legging, two main flaps of unequal length overlapping at their free edges, fastening means disposed adjacent said overlapping edges, a supplemental flap secured to the body portion and extending below the lower end of the shorter main flap, the free edge of said supplemental flap underlying at the free edge of the longer main flap throughout the length of the supplemental flap, and fastening means carried by said supplemental flap and the longer of said main flaps.

6. In a legging, a body portion comprising 65 two main flaps of unequal length overlapping at their free edges, fastening means disposed adjacent said overlapping edges, a shorter flap secured to the body portion and extending below the lower end of the shorter 70 main flap with its lower edge in a plane with the lower edge of the longer flap, and fastening means carried by said supplemental flap and one of the main flaps.

In testimony whereof I have signed my 75 name in presence of two subscribing witnesses.

THOMAS W. HAMILTON.
